UNITED STATES PATENT OFFICE.

JOZEF GUSTARA, OF MERRILL, MICHIGAN.

DESIGN FOR A SUGAR-BEET KNIFE.

46,878.

Specification for Design.

Patented Jan. 26, 1915.

Application filed October 24, 1914. Serial No. 868,535. Term of patent 7 years.

To all whom it may concern:

Be it known that I, JOZEF GUSTARA, a subject of the Emperor of Austria-Hungary, and residing at Merrill, Saginaw county, and State of Michigan, have invented a new, original, and ornamental Design for Sugar-Beet Knives, of which the following is a specification, reference being had to the accompanying drawing, forming part thereof.

The figure is a perspective view of a sugar beet knife, showing my new design.

I claim:

The ornamental design for a sugar beet knife as shown.

JOZEF GUSTARA.
